UNITED STATES PATENT OFFICE.

MILTON COHEN, OF NEW YORK, N. Y., ASSIGNOR TO ADLER ENGINEERING COMPANY, OF CORONA, LONG ISLAND, NEW YORK, A COPARTNERSHIP OF NEW YORK.

DENTAL ATTACHMENT FOR MOVABLE-REMOVABLE BRIDGWORK.

Application filed December 2, 1922. Serial No. 604,510.

To all whom it may concern:

Be it known that I, MILTON COHEN, a citizen of the United States of America, residing at New York city, in the county of 5 New York and State of New York, have invented certain new and useful Improvements in Dental Attachments for Movable-Removable Bridgework, of which the following is a specification, reference being 10 had therein to the accompanying drawing.

My invention relates to new and useful improvements in the construction of the dental attachments used for supporting movable-removable bridgework dentures in the 15 mouth.

That branch of dentistry known as movable-removable bridgework has for its purpose the restoration of one or more missing teeth, whereby the artificial removable 20 bridge denture that is fabricated by the dental operator to replace the missing tooth or teeth, is supported in the mouth in a restricted movable relationship to its stationary abutments, and is readily removed from 25 the mouth, at will. The dental attachment forming the substance of this invention, and composed of a male member that is adapted to be permanently mounted on the artificial removable denture, and a 30 female member that is adapted to be permanently supported on a stationary tooth in the mouth, termed an abutment, is the means whereby the artificial removable bridge denture is supported in the mouth.

A principal object of the invention is to 35 provide a dental attachment for movable-removable bridgework wherein the provision made for holding the removable bridge denture against unintentional dislodgment, 40 is supplied by the tension ability possessed by the male member of the attachment, by reason of the slot arrangement cut therein. Another principal aim of my invention is 45 to provide such a construction for the male member of my attachment, that there will be permitted a restricted movability for the removable bridge denture while held on its abutments in the mouth, relative to the stationary supporting abutments. A further 50 object of my invention is to provide a dental attachment for movably and removably supporting an artificial bridge denture in the mouth, that is simple in construction and positive in its functioning.

In view of the aforesaid objects, and the 55 further objects evident in the following description, the dental attachment forming the substance of this invention consists of the novel features of construction, and combination and arrangement of parts, herein- 60 after described and illustrated, and as particularly set forth in the claims appending this specification.

In the accompanying drawing I have 65 illustrated preferred embodiments of my invention, to attain the aforementioned objects, in which similar reference characters indicate corresponding parts in the various views.

In the accompanying drawing:

Figure 1 is a perspective view showing the female member of the attachment as used with the triangular shaped male member body.

Fig. 2 is a perspective view illustrating 75 my proposed method of construction for the male member of the attachment, embodying a triangular shaped male member body.

Fig. 3 is a perspective view, taken from the side opposite to that shown in Fig. 2, 80 illustrating my proposed method of construction for the male member of the attachment, embodying a triangular shaped male member body.

Fig. 4 is a view in elevation of the as- 85 sembly of the male and female members of the attachment, embodying a triangular shaped male member body, with a portion of the female member cut out.

Fig. 5 is a perspective view showing the 90 female member of the attachment as used with an oval shaped male member body.

Fig. 6 is a perspective view illustrating 95 my proposed method of construction for the male member of the attachment, embodying an oval shaped male member body.

Fig. 7 is a perspective view, taken from the opposite side to that shown in Fig. 6, 100 illustrating my proposed method of construction for the male member of the attachment, embodying an oval shaped male member body.

Fig. 8 is a perspective view showing the female member of the attachment as used with a rectangular shaped male member 105 body.

Fig. 9 is a perspective view illustrating 110 my proposed method of construction for

the male member of the attachment, embodying a rectangular shaped male member body.

Fig. 10 is a perspective view, taken from 5 the side opposite to that shown in Fig. 10, illustrating my proposed method of construction for the male member of the attachment, embodying a rectangular male member body.

10 Fig. 11 is a view in perspective of the artificial removable bridge denture in position between its abutments.

In Fig. 1, I show the female member of 15 the attachment to be used with the triangular shaped male member body, and composed of the flat back wall 1 with the sides 2 formed thereto at equal angles, this angle to be less than 90 degrees. The bottom 3 of the female member is flat, and is formed 20 to the flat back wall 1, at right angles. The formation of the female member is such as to produce a box-form, corresponding to the form of the body of the male member, the entire box-formed female member being fabricated preferably of one piece, as 25 this member is subjected to great heat while it is fixed in position on the abutment tooth.

Referring to Figures 2 and 3, wherein I 30 illustrate a male member with a triangular shaped body, I show this triangular shaped body 4 formed integral with the web 5, and at right angles thereto. The body 4 is made to taper from the top very slightly, and 35 may also be formed to the web 5 at any angle other than a right angle.

The body 4 of the male member, reference being had to Figures 2, 3, 4, 6, 7, 9 and 10, in each instance is provided with the 40 slots 6 and 7, extending longitudinally down from the top of the body over the greater part of its length, and of very narrow width, i. e., a few thousandths of an inch. These 45 slots 6 and 7 are cut transversely and completely across the body, being positioned one on each side of the longitudinal transverse plane through the center of the body.

Thus, when the male member is made to 50 engage within the female member, the body 4 of the male member will be wedged and held within the enclosure of the female member by the binding action of the upper lateral ends of the body 4, against the corresponding portion of the sides 2, of the female member. This binding action of the 55 upper lateral ends of the body 4 is existent by virtue of the yield or give of these lateral ends, across the areas of the corresponding slots 6 and 7. This restraining tension 60 against dislodgment possessed by the male member, by virtue of the existence of the slots 6 and 7, and therefore by the removable bridge denture to which the male member is fixedly supported, is such as to overcome 65 the unintentional dislodging tendencies dur-

ing mastication and similar natural actions, still permitting the removable bridge denture to be removed from the mouth, at will.

Referring to Fig. 4, it will be seen that the lower portion of the male member body 70 4 does not make contact, laterally, with the corresponding inner surface of the female member. The object of this is to give to the male member, and so to the removable bridge denture, a restricted rocking movement 75 due to the stress of mastication, corresponding to the natural tooth movement during mastication. However, this restricted rocking movement of the bridge denture, during mastication, takes place in one plane 80 only, i. e., in the plane parallel to the lateral plane of the body 4.

I have shown, in each case, the slots 6 and 7 to be equal in length, this having been 85 done arbitrarily. Again, in each of the aforementioned instances, I have also shown, arbitrarily, the slots 6 and 7 to be formed parallel to each other, and in planes parallel to the transverse plane through the center of the body 4. It may be found more desirable, in certain cases, to cut the slots 6 and 7 longitudinally through the body 4, so that their planes form similar angles with 90 the transverse plane through the center of the body. It is evident for mechanical reasons, to preferably position the slots 6 and 7 95 in planes proximally to the transverse plane through the center of the body 4, for then the greater portions of the body, i. e., those portions between the slots and the lateral 100 extremities of the body, will be tensioned when the body is made to engage within the female member.

Referring now to Fig. 11, I have illustrated an artificial removable bridge denture, 105 composed of an artificial first molar 8 and an artificial second bicuspid 9, rigidly mounted on the metallic saddle structure 10, the whole removable bridge denture being removably supported, in the mouth, on and between the 110 natural second molar 11 and natural first bicuspid 12, the latter two teeth acting as the abutments for the bridge denture. I have also assumed two attachments to be 115 used for supporting this removable bridge denture in the mouth. The male members of the attachments are permanently mounted, generally by the use of solder, on the saddle structure 10, one at each of its lateral extremities, and adjacent to the surfaces of 120 the two artificial teeth. The two female members of the attachments would then be supported, one on each abutment tooth, by being permanently mounted, generally by the use of solder also, in the metallic inlays 125 13, one seated in each abutment tooth. The method employed for mounting the male and female members of the attachments on the saddle structure and in the inlays, respectively, is understood to be consistent 130

with the proper technique for this branch of dentistry, and is well known to those skilled in this art and technique.

The removable bridge denture is placed 5 in the mouth, between its abutments, by permitting the male members of the attachments on the bridge denture saddle structure to engage within the corresponding female members on the abutments, the body of each 10 male member finding access into its female member only from the top, i. e., occlusally. After the removable bridge denture has been placed in position between its abutments in the mouth, it is so held against unintentional 15 dislodgment, by the tensioning action due to the slot arrangement in the body of each male member. The extent of this tensioning ability possessed by the male members, which can be adjusted, i. e., increased or de- 20 creased by increasing or decreasing the width of the slots 6 and 7, respectively, should be such as to hold the removable bridge denture in position in the mouth, against the dislodging tendencies due to mastication and 25 similar natural causes, but such as to permit the bridge denture to be readily removed from the mouth, at will.

In the accompanying drawing, I have illustrated in Figures 1, 2, 3 and 4 the embodiment of my invention, in the method 30 of dental attachment construction, in a triangular shaped attachment. Also in Figures 5, 6 and 7, I have illustrated the embodiment of my method of attachment construction in an oval shaped attachment, while in Figures 8, 9 and 10, the embodiment 35 is illustrated in a rectangular shaped attachment. Although I have illustrated the embodiment of my invention, in the method of dental attachment construction, 40 in only three different shapes or forms, I wish to set forth that the shape or form of the attachment embodying my invention is of secondary importance, the embodiment 45 being capable of employment in practically any type of dental attachment for removable bridgework, regardless of its form or shape. In Fig. 11, I have illustrated the attachment as used between the first and 50 second molars triangular in shape, while the one as used between the first and second bicuspids oval in shape, showing that two different shaped attachments, embodying my invention, can be readily used on the same bridge denture.

In the foregoing I have proposed that the 55 slots 6 and 7 be made as great in length as possible, consistent with the strength of the material, because it is often necessary to cut down the height of the male and female 60 members of the attachments in order to accommodate a tooth of low height. In fact, the slots should be made to extend over such a length of the male member, as to permit 65 the entire upper half of the male member

to be cut away, and still have the remaining half function with the same results as if the whole member were used. I have shown, in each instance, the slots as extending in straight lines, both longitudinally and transversely, just for convenience, these slots being formed just as readily in shape of a curve or angle. The material for fabricating, both members of the attachment, could be any non-corrosive metal, preferably, 70 platinum, palladium, gold, etc., or their alloys.

While I have herein illustrated and described my invention in considerable detail, I wish to set forth that modifications and changes thereof may be readily resorted to without departing from the spirit and scope 80 of the invention, as expressed in the pending claims.

What I claim is:

1. A dental attachment for movable-removable bridgework, composed of a box-formed jacket member adapted to be permanently seated on a stationary abutment tooth in the mouth, and a linking member adapted to be permanently supported on the artificial removable bridge denture, the said linking member comprising a web and a solid body formed at an angle to each other, the said body having cut therein two slots 95 extending longitudinally over the greater part of its length and disposed in planes transversely of the body one on each side of its central transverse plane; the said body being adapted to engage within the said jacket member and act as the means for holding the removable bridge denture on its abutments in the mouth against unintentional dislodgment, and in movable relationship to the said abutments. 100

2. In a dental attachment for removable bridge dentures, an open top box-formed jacket member positioned with a longitudinal breach, and a linking member, the said linking member comprising a web for permanently anchoring the linking member to the removable bridge denture and adapted to be disposed vertically movable in the breach of the said jacket member, and a substantially solid body element formed correspondingly to engage within the said jacket member, the said body element having cut completely across its section a plurality of parallel slots extending longitudinally down from the top the greater part of its length, 110 the said slots being disposed in planes transversing the body section and on both sides of the transverse plane through the center of the body. 115

3. A dental attachment for movable-removable bridgework, composing a box-formed jacket member adapted to be rigidly supported on an abutment tooth in the mouth, and a linking member adapted to be permanently supported on the artificial re- 125

movable bridge denture, the said linking member comprising a solid body element tapered somewhat towards its lower extremity and a web element formed at a right angle thereto, the said body element having positioned therethrough two slots extending longitudinally for the greater part of its length one on each side of the central transverse plane through body and web; the said body element being adaptedly shaped to engage within the said jacket member and provide by virtue of its slot arrangement, the tensioning means against unintentional dislodgment of the removable bridge from its abutments, at the same time providing a restricted movability or rocking movement for the removable bridge while so held.

4. In a removable bridge denture attachment of the character described, the combi-

nation of a symmetrically shaped box-formed member adapted to be permanently attached to an abutment tooth in the mouth, and a linking member for seating the removable denture in the mouth, the said linking member comprising a web element and a body element formed integrally and at an angle to each other, the said body element having cut transversely therethrough two slots not extending the full length thereof, each of the said slots being disposed in planes forming with the transverse plane through the center of the said body element an angle other than a straight angle (180 degrees) one on each side of the said central transverse plane through the body element and proximally thereto.

MILTON COHEN.
